UNITED STATES PATENT OFFICE.

KENNETH B. NOBLE, OF HARTFORD, CONNECTICUT.

CABLEWAY CARRIAGE.

Application filed February 28, 1925. Serial No. 12,446.

To all whom it may concern:

Be it known that I, KENNETH B. NOBLE, a citizen of the United States, and a resident of Hartford, in the county of Hartford and State of Connecticut, have invented new and Improved Cableway Carriages, of which the following is a specification.

My invention relates to the class of devices that are employed for carrying loads to different positions along a cableway and for elevating and lowering said loads in different positions in which the cable may be placed, and an object of my invention, among others, is to provide a device of this class that shall be simple in construction and particularly efficient in operation, simplicity in operation also being insured.

One form of device embodying my invention and in the construction and use of which the objects herein set out, as well as others, may be attained, is illustrated in the accompanying drawings, in which—

Figure 1 is a view in side elevation of my improved cableway carriage, a portion of the load suspending and releasing mechanism being shown in section.

Figure 2 is a view in side elevation of a portion of the load suspending and releasing mechanism looking in a direction at right angles from the point of view of Figure 1.

Figure 3 is a view in side elevation of a portion of said mechanism illustrating the operation of the levers in releasing a load.

My improved apparatus contemplates a structure that may be employed for use on a cable or rope irrespective of the direction in which said cable or rope may be inclined, or whether it be placed in a level position, the device being so arranged and constructed as to involve extreme simplicity in its operations, all of which operations, including movement of the carriage to any desired position, the raising of the load thereon, with the locking thereof in a raised position, and the unlocking of the same, are accomplished by means of two lines or cables extending from opposite ends of the carriage and wound upon non-reversing rotatable drums, and by the use simply of the customary clutch and brake for the drums of a hoisting device of ordinary and well known construction. Aside from such parts any other devices, cables, stops, springs or other adjustable devices for stopping, starting,

locking or raising the load at any selected point are not required.

In the accompanying drawings the numeral 5 indicates a cableway that may be suspended in any ordinary and usual manner and along which the carriage is moved for the purpose of locating the load in any desired position. This carriage comprises two side plates 6 that are suitably spaced apart to receive the cable 5 between them, suitable spacers being employed and the parts being secured together as by bolts 7. Carrier sheaves 8 are rotatably mounted between the side plates at the upper edge of the carriage, said sheaves being adapted to roll along the cable 5, and a hoisting sheave 9 is also rotatably mounted between the plates at a point below the cable 5, and as illustrated in Figure 1 of the drawings. A main carriage cable 10 is secured to the carriage at its front end, said cable passing to and being wound upon one of the drums of any suitable hoisting apparatus common to devices of this class for moving the carriage along the cableway 5. This hoisting apparatus may be comprised of two non-reversing drums, manually or power operated, as may be desired, mounted upon a suitable base and relatively located in a manner that will be readily understood by those skilled in this art, and for which reason a showing thereof is omitted herein, said drums being provided with means for independently rotating them, to permit either to remain at rest independently of the other and to retard their free rotation in a manner common to apparatus of this kind. Such an apparatus is illustrated in my co-pending application, the oath in which bears even date herewith, and to which reference may be had for a more thorough understanding of the apparatus if desired.

An operating line 11 extends to and is wound upon the other drum of said hoisting apparatus for hauling purposes and said line extends over the sheave 9 and downwardly between the side plates 6 through the bottom of a yoke 12, through the top of a housing 13 for a load supporting catch block 14, and through said catch block to which it is secured in any suitable manner, as by means of a wedge in a recess in the support held therein by means of a clamping screw 15, through which screw the line extends and to the free end of which a hook 16 may be secured, as shown in Figure 1 of

the drawings. This catch block may be of a size and weight to serve as a fall line ball if desired.

The yoke 12 is of U-shape as shown in Figure 2, the side parts being located outside of the plates 6 on opposite sides of the carriage, said yoke being pivotally attached to the carriage so that it will always assume a position to direct the line 11 vertically irrespective of any inclined position the carriage may have, as the cableway 5, in many instances, may be located in an inclined position, and in such case the carriage will assume a position as indicated by dotted lines in Figure 1. Only the carriage, however, is shown in dotted lines to indicate this inclined position, but in such position the operating and load supporting mechanism will be suspended vertically, as shown in full lines in this figure, although in a little different position from that shown.

The housing 13 has supporting lugs 17 on opposite sides thereof and supporting rods 18 secured to said lugs extend through guide lugs 19-20 projecting from the side of the yoke 12, the rods 18 being provided with any suitable means, as nuts in the construction herein shown, to limit the downward movement of the housing 13. Locking levers are pivotally supported in lugs 21 on opposite sides of the housing 13, these levers comprising load supporting latches 22 at their lower ends and latch disengaging cams 23 at their upper ends, said cams being located in position to make contact with the end of the yoke 12 when the housing 13 is raised, as by a pull upon the operating line 11. Said cams are offset, as shown in Figure 2 of the drawings, so that they will not interfere with the operating line 11 in its movements through the hole in the top of the housing 13 and said cams are of such weight with respect to the latches 22, and are so disposed relatively to said latches, that a slow swinging movement thereof is obtained, as compared with the movement of the catch block from within the housing, so that when the operating line 11 is loosened to permit the catch block to fall the latter will readily pass its lower edge below the engaging portions of the latches 22 before the latter have time to swing to their closed and locking position.

It will be understood that the cable 10 is passed around a sheave and from thence in a direction the same as that of the line 11, both of which are secured to the drums hereinbefore mentioned, so that both the line 11 and cable 10 may be operated from the same point.

In operation the carriage is moved to a desired position by a haul upon the operating line 11, with or without a load suspended therefrom, or a haul upon the main carriage

cable 10. If the load is in its lowered position the drum upon which the cable 10 is wound is held against rotation thereby resisting the pull upon the carriage as the load is being raised by a haul upon the operating line 11. A continued haul upon the operating line, after the load has been raised and locked in its raised position, will serve to move the carriage in one direction, the drum upon which the cable 10 is wound being released for such purpose and the drum upon which the line 11 is wound being rotated. A movement of the carriage in the opposite direction may be obtained by reversing this operation of the drums. When the carriage has been placed with the load in the desired position the release of the load supporting catch block is effected by a haul upon the line 11 through its operating drum that raises the housing 13 and the cam lever locks carried thereby, the latter into engagement with the yoke 12 whereby said lever locks are opened as shown in Figure 3 of the drawings. The operating line being now quickly released by a release of its operating break the catch block quickly passes its lower edge below the engaging portions of the supporting latches, and the load is lowered by a breaking action upon the drum. When the load is raised, as hereinbefore described, the latches will be engaged by the catch block and opened sufficiently to permit its passage and said latches will then automatically close to catch and hold said block.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A cable carriage with a support therefor, an operating line movably mounted on said carriage, a catch block secured to said line and relatively immovable thereof, a member to engage said block to retain it in a raised position, means operating by movement of said member to disengage the latter from said block and means operating when said member is stationary to engage it with said block.

2. A cable carriage with a support therefor, an operating line movably mounted on said carriage, a catch block secured to said line and relatively immovable thereof, a member to engage said block to retain it in a raised position, means located in the path of movement of said member to engage it when moved and disengage it from said block and means to engage said member

when it is stationary to engage it with said block.

3. A cable carriage including a support therefor, an operating line movably mounted on said carriage, a catch block secured to said line and relatively immovable thereof, a pair of latches pivotally mounted to engage said block and having disengaging cams, and means operative by a lengthwise movement of said line independently of said carriage to engage said cams and thereby disengage said latches from said block.

4. A cable carriage including a support therefor, an operating line movably mounted on said carriage, a catch block secured to said line, a pair of latches pivotally mounted to engage said block and having disengaging cams, means to bodily move said latches and cams, and means located in the path of movement of said cams to engage them when moved by a lengthwise movement of said line independently of said carriage and thereby disengage said latches from said block.

5. A cable carriage including a support therefor, an operating line movably mounted on said carriage, a catch block secured to said line, a yoke secured to said carriage, a member to engage said block to retain it in a raised position, and means operated by a lengthwise movement of a line independently of said carriage for moving said member against said yoke to disengage said member from said block.

6. A cable carriage including a support therefor, a yoke pivotally suspended from said carriage, an operating line movably mounted on said carriage and extending through said yoke, a catch block secured to said line, a member to engage said block to retain it in a raised position, and means operated by a lengthwise movement of a line independently of said carriage for carrying said member against said yoke to disengage said member from said block.

7. A cable carriage including a support therefor, an operating line movably mounted on said carriage, a catch block secured to said line, a supporting member located in the path of movement of said block, a retaining member vertically movable and pivotally mounted on said supporting member to engage said block to retain it in a raised position, and means against which said retaining member is carried by a lengthwise movement of said line independently of said carriage and thereby disengaged from said block.

8. A cable carriage including a support therefor, an operating line movably mounted on said carriage, a catch block secured to said line, a housing vertically movable and adapted to receive said block, a retaining member pivotally mounted on said housing to engage said block, and means located in

the path of movement of said retaining member caused by a lengthwise movement of said line independently of said carriage for engagement by said member to disengage it from said block.

9. A cable carriage including a support therefor, an operating line movably mounted on said carriage, a catch block secured to said line, a member vertically movable and located in the path of movement of said block, a pair of supporting latches pivotally mounted on said member and having disengaging cams, and means located in the path of movement of said cams caused by a lengthwise movement of said line independently of said carriage for engagement by said cams to disengage said latches.

10. A cable carriage including a support therefor, an operating line movably mounted on said carriage, a yoke pivotally mounted on said carriage and through which said line extends, a member through which said line loosely passes, a pair of supporting latches pivotally mounted on said member, and a catch block secured to said line for movement between said latches to support them and thereby be engaged by said latches for support thereby in a raised position.

11. A cable carriage including a support therefor, an operating line movably mounted on said carriage, a catch block secured to said line, a member suspended from said carriage and having a limited vertical movement independently thereof to engage said block to retain it in a raised position, and means operated by movement of said member caused by a lengthwise movement of said line independently of said carriage to disengage it from said block.

12. A cable carriage including a support therefor, an operating line movably mounted on said carriage, a yoke pivotally mounted on said carriage, a supporting member carried by said yoke and having a limited movement independently thereof, a catch block secured to said line, and a retaining member pivotally attached to said supporting member to engage said block and retain it in a raised position and to engage said yoke for disengagement of said member from said block.

13. A cable carriage including a support therefor, a yoke pivotally suspended from said carriage, a supporting member suspended from said yoke and having a limited movement independently thereof, an operating line movably mounted on said carriage and extending through said yoke and said supporting member, a catch block secured to said line in position to engage said supporting member, and a retaining member pivotally mounted on said supporting member in position to be moved against said yoke and thereby be disengaged from said block.

14. A cable carriage including a support therefor, a yoke pivotally suspended from said carriage, a housing suspended from said yoke and having a limited movement independently thereof, an operating line movably mounted on said carriage and extending loosely through said yoke and through said housing, a catch block secured to said line below said housing, and a pair of supporting latches pivotally mounted on said housing and having disengaging cams adapted to be carried against said yoke, said latches being positioned to engage said block when the latter is located in said housing. 45
15. A cable carriage with a support therefor, a main carriage cable for moving the carriage in one direction, an operating line for moving the carriage in the opposite direction, means secured to said operating line and relatively immovable thereof to receive a support and load, and means on said carriage to hold said load in a suspended position. 50
16. A cable carriage with a support therefor, a main carriage cable for moving the carriage in one direction, an operating line for moving the carriage in the opposite direction, means secured to said operating line and relatively immovable thereof to receive a support and load, and means on said carriage for locking it to hold said load in a suspended position and for releasing said lock. 55
17. A cable carriage with a support therefor, a main carriage cable for moving the carriage in one direction, an operating line for moving the carriage in the opposite direction, locking mechanism supported by said carriage, and means secured to said 60
18. A cable carriage with a support therefor, a main carriage cable for moving the carriage in one direction, an operating line for moving the carriage in the opposite direction, a pair of locking levers supported by the carriage, and means secured to said operating line and relatively immovable thereof and actuated by a lengthwise movement of said line independently of said carriage for releasing said lock. 65
19. A cable carriage with a support therefor, a main carriage cable for moving the carriage in one direction, an operating line for moving the carriage in the opposite direction, a pair of locking levers pivotally supported by said carriage and otherwise movable independently thereof, and means secured to said operating line and relatively immovable thereof and actuated by a lengthwise movement of said line independently of said carriage for actuating said locking levers. 70
20. A cable carriage with a support therefor, a main carriage cable for moving the carriage in one direction, a stop on said carriage, a member supported by said carriage for a limited vertical movement independently thereof, an operating line extending through said stop and through said member, a catch block secured to said line below said member, and a latch pivotally attached to said member for engagement of its end with said stop in the vertical movement of said member to disengage said latch from said block. 75

KENNETH B. NOBLE.
